United States Patent Office

Des. 230,160
Patented Jan. 29, 1974

230,160

TELEPHONE STAND

Donald Michael Genaro, Haworth, N.J., John Niel McGarvey, Drexel Hill, Pa., and Gordon Elliot Sylvester, Jamaica, N.Y., assignors to Bell Telephone Laboratories, Incorporated, Murray Hill, N.J.

Filed Apr. 13, 1973, Ser. No. 350,905

Term of patent 14 years

Int. Cl. D14—03

U.S. Cl. D26—14 A

FIG. 1

FIG. 2

FIG. 3

FIG. 4

FIG. 1 is a perspective view showing the top, back, and one side of our new design for a telephone stand;

FIG. 2 is a top plan view of the telephone stand;

FIG. 3 is a rear view of the telephone stand, the front view being essentially identical in elevation; and

FIG. 4 is a side view of the telephone stand, the opposite side being essentially a mirror image of the side shown.

We claim:

The ornamental design for a telephone stand, substantially as shown and described.
